UNITED STATES PATENT OFFICE.

THOMAS J. HART, OF CORNING, NEW YORK, ASSIGNOR TO INGERSOLL-RAND COMPANY, OF JERSEY CITY, NEW JERSEY, A CORPORATION OF NEW JERSEY.

COMPRESSOR-OVERLOAD REGULATOR.

1,378,028.

Specification of Letters Patent. Patented May 17, 1921.

Application filed August 7, 1918. Serial No. 248,811.

To all whom it may concern:

Be it known that I, THOMAS J. HART, a citizen of the United States, residing at Corning, in the county of Steuben and State 5 of New York, have invented a certain new and useful Improvement in Compressor-Overload Regulators, of which the following is a specification.

This invention relates to compressors, and 10 in particular to a compressor utilized for compressing natural gas for the extraction of gasoline. More especially the present invention relates to a compressor for this purpose provided with a regulator in the form 15 of an equalizer to prevent a change in intake pressure due to increased pressure within the well or other contained source from which the gas is drawn from unduly overloading the compressor.

20 The objects of the present invention are to provide an equalizer for this type of compressor which will be compact, cheap, simple and efficient and which will also prevent loss of gas.

25 In the process of extracting gasoline from natural gas the gas as it is pumped or flows from the well is passed through a compressor, usually one having two or three stages, the discharge pressure of the gas 30 after passing through the compressor being in the neighborhood of from two hundred pounds to three hundred pounds, the gasoline contained within the natural gas being precipitated from the intercooler between 35 the high pressure stages or from the high pressure discharge line. In this type of compressor the absolute pressure within the gas well fluctuates within wide limits and at times is several hundred per cent. greater

40 than at other times, which, if not compensated for will greatly overload the compressor when the pressure within the well rises above normal. To prevent this overloading by simple means is accomplished in 45 the manner brought out in the following description.

In the drawings annexed hereto and forming a part hereof,

50 Figure 1 shows diagrammatically a multi-stage compressor provided with the present form of equalizer; and

Fig. 2, a diagram showing the effect of variations of intake pressure of the gas being compressed upon the amount of com-

pression in each of the cylinders of the compressor. 55

Referring more particularly to the drawings, 1 refers to the low pressure or vacuum cylinder of a multi-stage compressor, and 2 the intercooler between the cylinder 1 and 60 intermediate cylinder 3. In this figure a third or high pressure cylinder is shown diagrammatically at 4 in alignment with the cylinder 3 and having an intercooler 5 interposed between it and the cylinder 3. 65

The intake 6 of the compressor which is in direct connection with the gas well serves to admit the gas into the cylinder 1. It is obvious that with the intake 6 connected with a large space filled with gas a distance 70 from the compressor and at great distances below the surface of the ground that the pressure therein will vary very greatly and if the pressure increases will allow a greater mass of gas to enter the cylinder 1 with 75 correspondingly increased work put upon the compressor. If the pressure within the well and consequently in the intake 6 is increased the amount of work may be greatly in excess of the capacity of the compressor 80 so that an equalizer must be provided to keep the work of the compressor balanced and within its normal capacity without unloading the units. For this purpose a by-pass conduit 7 is provided connecting the 85 discharge side of the low pressure cylinder 1 at the point it joins the intercooler 2 with the intake 6. Within this by-pass conduit 7 is located a valve body 9 having a valve member 10 held against its seat by means of 90 a compressive spring 11 the pressure of which against the valve 10 may be regulated by means of a wheel 12.

In the operation of the compressor, the increase in the intake pressure 6 will cause 95 a corresponding increase in the pressure in the discharge at 8 and also in the intercooler 2 until a point is reached when the discharge pressure in 8 and in the intercooler 2 is sufficient to overcome the pressure of spring 11 100 in the valve body 9 which will cause the valve 10 to open and allow the excess gas to flow back into the intake 6. In this manner the load on the compressor is kept from exceeding a given maximum and the excess 105 gas is returned to the intake without loss and without unloading the compressor. Also, should the valves in the intermediate

and high pressure cylinders of the compressor become inoperative or leak, thus causing gas to leak back into the intercooler 2, the valve 10 will come into operation to prevent the compressor cylinder becoming overloaded. The force of the spring 11 may readily be varied by means of the wheel 12 so that the valve 9 will open at any pressure for which it is set and for which 10 the compressor is adapted.

Referring briefly to Fig. 2, this figure shows diagrammatically the effects upon the compressor in each stage when variations in the intake pressure take place. The sectioned areas 13, 14, 15 show the amount of work done in each stage of the compressor when the intake is at normal pressure. As seen by these areas 13, 14, 15, the work done in each cylinder is approximately equal. With an increase in intake pressure the work done in the cylinders or stages is represented by the areas 16, 17 and 18, included within the fine lines. From these it will be seen that the work required of the low pressure cylinder represented by area 16 is far greater than that normally required as represented by area 13, and also greatly in excess of strength. The work required by the other cylinders as shown by a comparison of areas 17 and 14, and 18 and 15 shows that the work done in the intermediate cylinder is greatly enlarged but not to the same extent as the work of the low pressure cylinder.

In further explanation of Fig. 2, it may be said that in said figure ordinates represent pressures and the abscissæ represent the length of stroke as usual. The base is taken as absolute pressure and the line 20 indicates atmospheric pressure. The sectioned area 13 as stated represents the diagram with a minimum or normal intake pressure, while the dotted lines 21 indicate the desirable diagram with a somewhat higher intake pressure.

The diagram indicated by the full lines 16 would be approximately obtained without control of the intake pressure. As shown, the pressure would rise from about the 50 point 22, which indicates approximately the outlet pressure desired, and the arrow pointed line 23 extending between the points 22

and 24 serves to indicate graphically the difference between the diagram 21 in dotted lines and the diagram 16 in full lines. 55

As stated, the sectioned area 14 represents the diagram in the second stage with a normal intake pressure and the area 15 represents the normal diagram in the third stage. The areas 17 and 18 in full lines indicate the diagrams in these stages corresponding to the diagram 16 in the first stage with increased intake pressure and no regulation. The lines 25, 26, 27, 28 and 29 show diagrammatically the proportionate work 65 done in each stage at the different pressures, because in each rectangular area formed by said lines the work diagrams are indicated.

From the above description and explanation it will be seen that a simple and efficient equalizer has been devised which will limit the work accomplished by the compressor in order to prevent an overload beyond the capacity of the compressor and keep the machine balanced. 70

It is to be understood that the present showing and description discloses only one specific embodiment of the present invention and that other forms and modifications are included within the spirit and scope of the 80 invention, as expressed in the appended claim. 75

What I claim is:

A regulating system for producing a constant quantity of discharge from the high pressure cylinder of a compound compressor without varying the speed or unloading the machine, in which both the intake and the discharge pressures are variable, comprising a low pressure cylinder, an intercooler, and 90 at least one high pressure cylinder, a by-pass from the intercooler to the intake of the low pressure cylinder, and a pressure relief valve in said by-pass, adapted to open communication from the intercooler to the 95 intake of the low pressure cylinder at a predetermined pressure in the intercooler, thereby maintaining constant pressure in the intercooler and constant quantity of intake into the high pressure cylinder. 100

In testimony whereof, I have hereunto set my hand.

THOMAS J. HART.
